UNITED STATES PATENT OFFICE.

WALTER O. LUM, OF PITTSBURGH, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,352,462.

Specification of Letters Patent. Patented Sept. 14, 1920.

Application filed May 27, 1916. Serial No. 100,371.

To all whom it may concern:

Be it known that I, WALTER O. LUM, a citizen of the United States, and a resident of Pittsburgh, in the county of Allegheny and State of Pennsylvania, have invented a new and useful Improvement in Circuit-Interrupters, of which the following is a specification.

My invention relates to circuit interrupters and particularly to means for damping or retarding the movement of the movable members of the same during its opening operation.

The object of my invention is to provide a device of the above indicated character that shall be cheap to construct, efficient in operation and readily attachable to the ordinary types of oil-insulated circuit interrupters.

It is a well known fact that considerable jarring is experienced when a circuit interrupter is tripped unless some form of shock-absorbing device is provided. In view of the above, I provide vanes that are attached to the movable member of an oil-insulated circuit interrupter and adapted to be normally disposed substantially in alignment with the direction of movement of the contact members to preclude any opposition to the closing operation of the interrupter. The vanes are so positioned and so shaped that, when the contact members are separated, the vanes gradually assume a position which is normal to the direction of the movement of the movable contact members, thus retarding its movement toward the latter part of its opening operation to preclude the shocks that are usually incident to such operations.

Figure 1 of the accompanying drawing is a side view, partially in section and partially in elevation, of a circuit interrupter embodying my invention, Fig. 2 is an end view, partially in section and partially in elevation, of the circuit interrupter shown in Fig. 1, and Figs. 3 and 4 are detail views of modified forms of vanes embodying my invention.

A circuit interrupter 1 comprises stationary contact members 2, a movable supporting member 3, movable contact members 4 and 5 and an oil-containing receptacle 6. The stationary contact members 2 are adapted to be supported by rods 7, and the mov-

able member 3 is adapted to be supported by an actuating rod 8.

Vaness 9 are pivotally supported by pins 10 that are carried by projections 11 on the sides of the movable member 3. The vanes are provided with bent portions 12 at their outer ends and are adapted to normally assume the positions shown in full lines in the drawings.

When the movable member 3 is moved upwardly to effect engagement of the contact members, the portions 12 of the vanes 9 so engage the oil 13 in which the contact members are immersed that the vanes are retained in such position as not to retard the movement of the movable member 3. However, when the movable member 3 moves downwardly, the portions 12 tend to engage the oil in such manner that the vanes 9 gradually assume a position which is normal to the direction of movement of the movable member 3. That is, the vanes 9 assume the positions shown in the broken lines in the drawing, and, in such positions, coöperate with the oil to retard the movement of the movable member 3 toward the latter part of its opening operation. The vanes 9 are provided with projections 14 for engaging the member 3 to prevent the vanes turning to a position other than that shown in the broken lines in Fig. 2 of the drawing.

If vanes having the shape of those shown in Fig. 3 are used, they will assume positions normal to the direction of movement of the movable member before the movable member has traveled an appreciable distance downwardly, and, if vanes having the shape of those shown in Fig. 4 are used, they will require a relatively greater movement of the movable member before they assume positions normal to the direction of movement of the movable member. Thus, the amount and the time of the retardation may be adjusted by the use of vanes of different shapes.

I do not limit my invention to the particular structure illustrated, as many modifications may be made therein without departing from the spirit and scope of the invention as set forth in the appended claims.

I claim as my invention:

1. The combination with a movable member for actuation in a fluid, of means, on

said member only, opposing the movement thereof by gradually changing amounts.

2. The combination with a movable member for actuation in a fluid, of means, on 5 said member only, opposing the movement thereof by constantly changing amounts substantially throughout its movement.

3. The combination with a movable member for actuation in a fluid, of means, on 10 said member only, opposing the movement thereof by gradually increasing amounts in one direction and by gradually decreasing amounts in another direction.

4. The combination with a movable member for actuation in a fluid, of means opposing the movement thereof by gradually changing amounts between positions where 15 said means effects substantially no opposition and where it effects its maximum 20 position.

5. The combination with a movable member for actuation in a fluid, of a vane pivoted to the movable member to effect a gradually changing amount of opposition there- 25 to during the movement of said movable member.

6. In a fluid-containing receptacle, the combination with a reciprocable member, of 30 a vane pivoted to the said member and adapted to be normally disposed in alignment with the direction of movement of the reciprocable member, said vane being provided with means whereby it assumes a 35 position normal to the direction of movement of the said member only when the said member is moved in one direction.

7. In a fluid-containing receptacle, the combination with a reciprocable member, of 35 vanes pivoted to the reciprocable member

and having outwardly extending end por- 40 tions for causing the vanes to normally assume a position substantially in alignment with the direction of movement of the said member.

8. In a fluid-containing receptacle, the 45 combination with a movable member, of vanes pivoted to the movable member and normally positioned substantially in alignment with the direction of movement of the movable member, said vanes having bent 50 outer ends for assisting the vanes to assume positions substantially normal to the direction of movement when the movable member is moved in one direction.

9. A retarding device for a movable mem- 55 ber comprising a fluid-containing receptacle and a relatively-movable vane mounted on the movable member to assume positions of maximum and substantially zero retarding effects with respect thereto.

10. A retarding device for a movable member comprising a fluid-containing receptacle and a relatively-movable vane mounted on the movable member to oppose the movement thereof by gradually increasing 65 amounts in one direction and to assist the movement thereof by gradually lowering its opposition with respect thereto in another direction.

11. The combination with a movable 70 member for actuation in a fluid, of means for retarding the movement thereof by forces ranging in value from substantially zero to a maximum.

In testimony whereof, I have hereunto 75 subscribed my name this 12th day of May 1916.

WALTER O. LUM.
